CLAIM

The ornamental design for a table, as shown and described.

DESCRIPTION

FIG. 1 is a front view of a table according to the design; FIG. 2 is a right, front perspective view thereof; FIG. 3 is a left, side perspective view thereof; FIG. 4 is a right side view thereof; FIG. 5 is a left side view thereof; FIG. 6 is a top view thereof; FIG. 7 is a bottom view thereof; and, FIG. 8 is a rear view thereof.

The broken lines in the drawings and the lightened areas within the broken lines illustrate portions of the table that form no part of the claimed design.
